UNITED STATES PATENT OFFICE.

PAUL FRANCIS LA GREE, OF CHICAGO, ILLINOIS.

COUPLING.

1,157,401.

Specification of Letters Patent. Patented Oct. 19, 1915.

Application filed May 15, 1914. Serial No. 838,737.

To all whom it may concern:

Be it known that I, PAUL FRANCIS LA GREE, a citizen of the United States, residing at Chicago, in the county of Cook and 5 State of Illinois, have invented certain new and useful Improvements in Couplings, of which the following is a specification.

The present invention relates to couplings, and while particularly intended for securing 10 a nozzle to a hose, is not necessarily limited thereto.

The primary object of the present invention is to provide novel and simple means of an effective character, whereby the members 15 can be quickly coupled and detached, and when in coacting relation, will be securely maintained in such relation.

An embodiment of the invention that is at present considered preferable, is illustrated 20 in the accompanying drawings, wherein:—

Figure 1 is a side elevation of the coupling in assembled condition. Fig. 2 is a similar view at right angles to Fig. 1. Fig. 3 is a longitudinal sectional view, and Fig. 4 is a 25 cross sectional view.

Similar reference numerals designate corresponding parts in all the figures of the drawings.

In the embodiment illustrated, the two 30 members to be coupled are respectively designated 5 and 6, being tubular in form, and one having its bore at one end enlarged, as illustrated at 7. The coacting end of the other member is externally tapered, as illustrated 35 at 8, to fit therein.

One of the members, as 5, is provided with 40 outstanding lugs 9, to which are pivoted holding arms. Each of these arms consists of sections 10 and 11, the section 10 being bifurcated at one end to straddle the lug 9, as illustrated at 12, the said end and lug having a pivot 13 passed therethrough. The two sections are adjustably connected by a bolt 14 having reverse threads on its opposite ends, said ends being screwed respectively into the two sections. The central portion of the bolt is angular in cross section, as illustrated at 15 to afford a head for the application of a wrench or other device. Lock nuts 16 are employed for preventing the accidental turning of the bolt. The section 6 is provided with oppositely disposed outstanding projections or lugs 17 that are rounded and are adapted to pass 55 into and through sockets 18 formed in the

sections 11 of the arms. The two members 5 and 6 are thus adjustably connected.

In order to retain the parts in their operative position, a ring 19 is slidably and rotatably mounted on the member 6, its sliding movement being limited by stops 20 and 21 located on opposite sides of said ring. This ring is provided with an internal socket groove 22 that has a reduced portion 23 opening through one side of the ring and 60 having a pair of opposite enlargements 24. The free ends of the holding arms are provided with outstanding transversely disposed ears 25 that are arranged to pass through the enlargements 24 when the latter 65 are registered therewith and the ring is moved longitudinally toward the arms. When said ears 25 are within the socket groove 22, the ring can then be rotated until the enlargements 24 are out of register with 70 the ears 25. The rotary movement of the ring is limited by internal stops 26 that abut against said ears.

It is believed the manner of operating the coupling will be obvious. Assuming the 80 parts in assembled relation, as illustrated, it is only necessary to rotate the ring 19 until the enlargements 24 are in line with the ears 25, when said ring can be moved rearwardly, thereby releasing the arms. 85 These arms can then be swung outwardly, and the coupling members separated. A reverse operation locks the members together and maintains them effectively in assembled relation. By having the arms extensible, all 90 wear and slight differences between the parts can be provided for, thus insuring a tight joint between the members.

From the foregoing, it is thought that the construction operation and many advantages 95 of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new and desire to secure by Letters Patent, is:—

1. A coupling of the character set forth, comprising coacting tubular members, an arm pivoted to one member and detachably interlocking with the other member to hold 110

said members against relative longitudinal movements, and a locking device for the arm, slidably mounted on said other member, said arm and device being provided with interlocking means for retaining said device against longitudinal movement when in locking position.

2. A coupling of the character set forth, comprising coacting tubular members, an 10 arm pivoted to one member, and detachably interlocking with the other member, said arm being provided with a lug, and a device slidably and rotatably mounted on said other member, to interlock with said lug on 15 the arm and hold the latter in its interlocking relation.

3. A coupling of the character set forth, comprising coacting tubular members, an 20 arm movably mounted on one member said arm being provided with a lug and detachably interlocking with the other member, and a ring having an internal socket groove 25 opening through one side, said ring being slidable longitudinally of the member over the arm and rotatable to interlock with the lug on said arm.

4. A coupling of the character set forth, comprising coacting tubular members, an arm pivoted to one member and having an 30 interlocking engagement with the other member, said arm having an outstanding ear on its free end, and a ring having an internal socket groove opening through one side and having an enlargement at one point 35 to receive the ear, said ring being slidable longitudinally of the member over the arm and being rotatable to interlock with said ear.

5. A coupling of the character set forth, 40 comprising coacting tubular members, an arm pivoted to one member and having a socket, an outstanding projection on the other member that is received by the socket, said arm having an outstanding ear on its 45 free end, a ring slidably and rotatably mounted on said other member and having an internal socket groove opening through one side to permit the passage of the arm, said groove having an enlargement at one 50 point to permit the passage of the ear, a stop within the socket groove adapted to abut

against the arm and limit the rotatable movement of the ring, and stops mounted on said other member on opposite sides of the ring to limit its sliding movement.

55

6. A coupling of the character set forth, comprising coacting tubular members, extensible arms pivoted to one member and each comprising sections, a coupling bolt adjustably threaded into the sections for 60 holding them at different distances apart, means on the other coupling member for detachably interlocking with the arms, and a retaining ring slidably and rotatably mounted on said other member and engaging the arms to hold them in their interlocking relation.

65

7. A coupling of the character set forth, comprising coacting tubular members, an 70 outstanding lug carried by one member, an arm movably mounted on the other member and detachably interlocking with said lug, a ring slidably mounted on the first-mentioned member to engage said arm and hold the same in its interlocking relation with 75 said lug, and stops mounted on the first-mentioned member on opposite sides of the ring to limit the sliding movements of the latter, one of said stops being located between the ring and the lug.

80

8. A coupling of the character set forth, comprising coacting tubular members, an arm pivoted to one member and having a 85 socket, an outstanding projection on the other member that is received by the socket, said arm having an outstanding ear on its free end, a ring slidably and rotatably mounted on said other member and having an internal socket groove opening through one side to permit the passage of the arm, 90 said groove having an enlargement at one point to permit the passage of the ear, and a stop within the socket groove adapted to abut against the arm and limit the rotatable movement of the ring.

95

In testimony whereof I affix my signature in presence of two witnesses.

PAUL FRANCIS LA GREE.
